ABSTRACT

A viscous end-of-run and jam sensor and indicator for a cassette-type motion picture camera. A drag disk is mounted for rotation about the axis of rotation of the film take-up assembly and has a drag surface in closely-spaced juxtaposition with a rotatably-driven annular surface of the film take-up assembly. A quantity of viscous fluid is disposed between the drag surface and the rotatably-driven surface to form a viscous coupling therebetween to impart torque to the drag disk during rotation of the film take-up assembly. The drag surface and the rotatably-driven surface have continuous peripheral portions which define a small acute angle of divergence sufficient to effect retention of the viscous fluid between the drag surface and the driven surface by capillary attraction. A bias spring maintains the drag disk in a predetermined quiescent position in the absence of rotation of the film take-up assembly. An electrical circuit includes in series connection a voltage source, a manually-actuatable camera-actuation switch, a sensing switch, and an indicator lamp. The sensing switch is maintained closed by an arm extending from the drag disk when the drag disk is in its quiescent position. The indicator lamp thus will be energized in response to a cessation of rotation of the film take-up assembly due to the end of the run of the film or a film jam occurring while the camera-actuation switch is closed.

VISCOUS SENSOR

This invention relates to a viscous sensor and, in particular, to a viscous sensor for web handling mechanisms.

In certain web handling mechanisms, a rotary assembly is provided to take up the web or film which has been passed through the mechanism by winding the same onto a reel. In many instances, operation of the mechanism can be significantly facilitated if the instantaneous rotary condition of the take-up assembly can continuously be sensed for the purpose of providing an alarm or control signal. For example, in a cassette-type motion picture camera, the sensing of a cessation of rotation of the film take-up assembly during camera operation may be used to initiate an alarm signal indicating that the end of the film has been reached or that the film has jammed. It is a principal object of the present invention to provide viscous means for sensing cessation of rotation in a rotary assembly of a web handling mechanism.

The present invention incorporates a drag element mounted for rotation about the axis of the web or film take-up assembly and having a drag surface in closely-spaced juxtaposition with a rotatably-driven surface of the take-up assembly. A quantity of fluid having a selected viscosity characteristic is disposed between the drag surface and the driven surface to form a viscous coupling for imparting torque from the take-up assembly to the drag element. Means responsive to the drag element are provided to generate an indicating signal.

A troublesome problem attending the provision of a viscous coupling is that of retaining the viscous fluid between the drag surface and the driven surface without leakage. Accordingly, it is another important object of the present invention to provide a leak-proof viscous coupling. This is achieved in the present invention by providing a drag surface and a driven surface which are compatibly configured to have continuous peripheral portions defining an acute angle of divergence to effect retention of the viscous fluid between the drag surface and the driven surface by capillary attraction.

Additional features of the present invention include the provision of bias means effective to maintain the drag element in a predetermined quiescent position restrained against movement in the direction of rotation of the take-up assembly when the rate of rotation of the rotatably driven surface of the take-up assembly is less than a predetermined rate and the provision of electrical circuit means including switch means responsive to the position of the drag element to provide a signal indicative of the rotary condition of the take-up assembly. Preferably, the switch means comprises a switch which is adapted to be opened when sufficient torque is imparted to the drag element by the take-up assembly, and closed by the drag element when the drag element is in its quiescent position, closure of the switch being effective to produce a signal indicating that the rate of rotation of the take-up assembly is less than a predetermined rate.

These and other features and objects of the present invention will be better understood by reference to the following detailed description and the appended drawings.

IN THE DRAWINGS:

FIG. 1 is an elevational view of a preferred embodiment of the present invention.

FIG. 2 is a cross-sectional view taken along lines 2-2 of FIG. 1.

FIG. 3 is an enlarged view of a portion of FIG. 2.

FIG. 4 is an isometric view to illustrate the positioning of a leaf spring retaining member used in the preferred embodiment.

Referring now to the drawings, a preferred embodiment of the invention is shown for providing an end-of-run and jam alarm signal in a motion picture camera. The structure is mounted in a housing or frame 10 of a motion picture camera in association with the film take-up assembly of the camera.

The camera take-up assembly includes an input drive shaft 12 journaled through a positioning member 14 integral with the housing 10. The shaft 12 is driven by the camera drive (not shown) and is provided with a worm-threaded end portion 16 for driving a gear ring 18 in worm-gear driving engagement.

The gear ring 18 is rotatably mounted on an output take-up shaft 20 which is rotatably journaled at one end in an opening 22 in the housing 10 for rotatably driving a take-up reel driving disk 24. The reel mounting disk 24 is affixed to the take-up shaft 20 by a coaxially positioned screw 26 or other suitable fastening means and includes suitable reel driving elements 28.

The take-up shaft 20 is supported and positioned at its opposite end by a coaxial bearing pin 30 which is passed through an elongate bracket 32 and received within a central axial bore 34 in the take-up shaft 20. The bracket 32 is affixed at each end to the camera housing 10 by screws 36 or other suitable fastening means. A bearing bushing 38 is interposed between the bracket 32 and the associated end of the take-up shaft 20.

The gear ring 18 is provided on one side with an annular cavity 40 within which a radially extending integral annular flange 42 of the take-up shaft 20 is partially received. On its opposite side, the gear ring 18 is positioned by a disk 46 which is also mounted on the shaft 20. A leaf spring retaining member 48 is keyed to both the shaft 20 and the retaining disk 46 and serves to bias both the disk 46 and the flange 42 into frictional engagement with the gear ring 18. As depicted in FIG. 4, the exterior projections 49 and 50 of the leaf spring retaining member 48 are received within the slots 51 and 53, respectively, of the retaining disk 46. The interior projections 55 and 57 of the retaining member 48 are received within slots 59 and 61, respectively, provided in the take-up shaft 20 (see FIGS. 2 and 4). In this manner the retaining member 48 is keyed to both the take-up shaft 20 and the retaining disk 46. In position, the leaf spring retaining member is bowed resiliently (see FIG. 4) to develop the requisite bias force urging both the disk 46 and the take-up shaft flange 42 into frictional engagement with the gear ring 18 for frictional transmission of torque from the driven gear ring 18 to the take-up shaft 20.

A drag disk 52 is rotatably mounted on an annular collar 54 of the take-up shaft 20 to provide an annular drag surface 56 in juxtaposition with the annular driven surface 58 of the take-up shaft flange 42. A compression coil spring 60 is interposed between the housing 10 of the camera and the drag disk 52 to bias the drag disk 52 toward the annular flange 42. The drag surface 56 and the annular surface 58 form a drag transmission re-

gion therebetween in which a quantity of viscous fluid 62 is disposed. The fluid 62 has a viscosity sufficient to form a viscous coupling between the drag surface 56 and the annular driven surface 58 for imparting slip torque from the take-up shaft 20 to the drag disk 52.

It is important to note that the annular crowned surface 58 of the take-up flange 42 and the planar drag surface 56 of the drag disk 52 are compatibly configured to have continuous annular peripheral portions 64 and 68 along their outer periphery which cooperate to define a small acute angle X of divergence radially outwardly and continuous annular peripheral portions 66 and 70 which cooperate to define a small acute angle X' of divergence radially inwardly. The acute angles X and X' are sufficient to effect leak-proof retention of the viscous fluid 62 between the drag surface 56 of the drag disk 52 and the annular driven surface 58 of the take-up shaft flange 42 by capillary attraction eliminating the need for additional sealing rings and the like. The angles X and X' are preferably, but not necessarily, equal to one another.

It is apparent that either or both the annular driven surface 58 and the drag surface 56 may be suitably crowned, beveled, or otherwise provided with inclined peripheral portions to cooperatively define the requisite angles of divergence X and X' for viscous fluid retention. In the exemplary embodiment shown, the drag surface 56 is planar, and the annular driven surface 58 is inclined radially outwardly at portion 64 from an annular crown 72 to the outer diameter of the driven surface 58 and is inclined radially inwardly at portion 66 from the annular crown 72 to the inner diameter of the driven surface 58. In this connection, it should further be noted that the inner and outer diameters of the driven surface 58 are preferably, but not necessarily, equal to the inner and outer diameters, respectively, of the drag surface 56.

The drag disk 52 is provided with an integral radially extending arm 74 which is biased by an elongate coil spring 78 toward a predetermined limit position (shown in elevation in FIG. 1) against the body of a sensing switch 76 rigidly affixed to the housing 10 of the camera. The elongate coil spring 78 is engaged at one end to an engagement member 80 which is rigidly affixed to the housing 10 of the camera. The opposite end of the spring 78 is engaged in a recess 82 in the drag disk arm 74, and the spring 78 is arranged in a C-shaped configuration as depicted in FIG. 1 to develop a bias force in the direction indicated by the arrow 84.

The sensing switch 76 is provided with contacts 86 and 88 which are connected in series with the normally open contacts 94 and 96 of a camera-actuation or control switch 90 mounted to the camera housing 10 and adapted to be closed by manual depression of the associated camera-actuation button 92. The camera-actuation switch 90 would normally include two or more additional contact elements (not shown) connected in circuit to actuate the camera drive when the actuation button is depressed. The sensing switch 76 and the camera-actuation switch 90 are further electrically connected in series with a voltage source in the form of one or more battery cells 98 and with an indicator lamp 99 positioned adjacent an aperture 100 in the camera housing 10.

In operation with the camera-actuation switch 90 closed by manual depression of the button 92, rotation of the film take-up shaft 20 at normal speeds will impart to the drag disk 52 a slip or drag torque in the direction indicated by the arrow 102 sufficient to partially rotate the drag disk 52 and angularly displace the extending arm 74 away from the limit position shown in elevation in FIG. 1 and against the bias exerted by the spring 78, thereby opening the sensing switch 76.

More specifically, the extending arm 74 will be displaced to an equilibrium position as shown in phantom view in FIG. 1 at which the drag torque imparted to the drag disk 52 by the viscous coupling is in equilibrium with the increased bias force developed by the bias spring 78.

Should the take-up shaft begin rotating at an abnormally low rate or cease rotating entirely due to the occurrence of the end of the run or to a film jam while the camera-actuation switch 90 is closed, the bias spring 78 will return the arm 74 to its limit position, closing the sensing switch 76 to complete the series circuit and thereby energizing the indicator lamp 99 to provide a visual alarm signal to the operator. Whether an alarm indication will be given only when the take-up shaft stops entirely or also when the rate of rotation of the take-up shaft falls below a predetermined minimum rate will depend upon the design level of bias force to be exerted by the bias spring 78 and other related design parameters.

It will be apparent to those skilled in the art that the particular embodiment shown and described herein by way of example may be modified in various respects without departing from the scope of the inventive concepts.

What is claimed is:

1. In a web handling mechanism having a rotatably driven member, the combination therewith of a sensor comprising:

a rotatably mounted drag element having a drag surface in closely spaced juxtaposition with an adjacent surface of said rotatably driven member; a quantity of fluid having a selected viscosity characteristic disposed between said drag surface and said adjacent surface of said rotatably driven member to form a viscous coupling, said drag surface and said adjacent surface being compatibly configured to have continuous peripheral portions defining an acute angle of divergence to effect retention of said viscous fluid between said drag surface and said adjacent surface by capillary attraction; and signal producing means responsive to said drag element for providing an indicating signal.

2. The invention defined in claim 1 wherein said drag surface and said adjacent surface of said rotatably driven member are substantially radially oriented surfaces, at least one of said radially oriented surfaces having an inclined portion to provide said acute angle of divergence.

3. The invention defined in claim 1 further comprising resilient means axially urging said drag element toward said adjacent surface of said rotatably driven member.

4. The invention defined in claim 1 further comprising bias means effective to maintain said drag element in a predetermined position restrained against rotative movement when the rate of rotation of said rotatably driven member is less than a predetermined rate, said

signal producing means being responsive to departure of said drag element from said predetermined position to provide a signal indicating that the rate of rotation of said rotatably driven member is less than said predetermined rate.

5. In a web handling mechanism having a rotatably-driven web take-up assembly, the combination there-with of a sensor comprising:

a drag disk mounted for rotation about the axis of said web take-up assembly and having an annular 10 radially oriented drag surface in closely spaced juxtaposition with an annular rotatably driven radially oriented surface of said web take-up assembly; a quantity of fluid having a selected viscosity characteristic disposed between said annular drag surface 15 and said annular rotatably driven surface to form a viscous coupling, said annular drag surface and said annular rotatably driven surface cooperating to define an annular drag transmission region having an inner annular periphery and an outer annular periphery, said annular drag surface and said annular rotatably driven surface being compatibly 20 configured continuously along said inner and outer annular peripheries to define a small acute angle of divergence sufficient to effect retention of said viscous fluid within said drag force transmission region by capillary attraction; means urging said drag element toward said annular 25 rotatably driven surface; bias means effective to maintain said drag element in a quiescent position restrained against rotation in the direction of rotation of said web take-up assembly when the rate of rotation of said rotatably driven surface is less than a predetermined rate, said drag element being maintained in an equilibrium position when said rotatably-driven surface is equal to said predetermined rate; and electrical circuit means, including switch means responsive to the position of said drag element, for providing an output signal.

6. The invention defined in claim 5 wherein at least one of said annular surfaces includes inclined portions to provide said small acute angle of divergence along said inner annular periphery and along said outer annular periphery.

7. The invention defined in claim 5 wherein said switch means include a switch adapted to be opened when said drag element is maintained in said equilibrium position, and closed when said drag element is in said quiescent position, closure of said switch being effective to produce a signal indicating that the rate of rotation of said web take-up is less than said predetermined rate.

8. In a motion picture camera, the combination comprising:

a drive film take-up shaft; a radially extending annular flange affixed to said take-up shaft;

a drag disk rotatably mounted on said shaft in closely spaced juxtaposition with said annular flange and having an extending arm;

resilient means biasing said drag disk axially toward said annular flange;

a quantity of fluid having a selected viscosity characteristic disposed between said drag disk and said annular flange to form a viscous coupling, said annular flange and said drag disk being compatibly configured to have continuous peripheral portions to define a small acute angle of divergence sufficient to effect retention of said viscous fluid between said annular flange and said drag disk sufficient to impart drag torque to said drag disk during rotation of said take-up shaft;

bias means effective to maintain said drag disk in a predetermined quiescent position in the absence of rotation of said film take-up assembly; and

an electrical circuit including in series connection a voltage source, a first camera-actuation switch, a second switch disposed in proximity to said extending arm when said drag disk is in said predetermined quiescent position, whereby said indicator lamp will be energized in response to a cessation of rotation of said film take-up shaft while said camera-actuation switch is closed.

9. The invention defined in claim 8 wherein said drag disk is configured to present an annular planar drag surface in juxtaposition to said annular flange, said drag surface having an inner diameter substantially equal to the inner diameter of said annular flange and an outer diameter substantially equal to the outer diameter of said annular flange, and wherein said annular flange, in turn, is configured to present an annular crowned surface in juxtaposition to said drag surface of said drag disk, said crowned surface being divergently inclined at 35 said small acute angle in proximity of said outer diameter of said annular flange, said crowned surface further being divergently inclined at said small acute angle proximity of said inner diameter of said annular flange.

45 10. The invention defined in claim 9 wherein said bias means comprises a coil spring fixedly positioned at one end and engaged at its opposite end with said extending arm of said drag disk.

50 11. The invention defined in claim 10 wherein said coil spring is arranged in a C-shaped configuration biasing said extending arm of said drag disk in a direction opposite to the direction of rotation of said take-up shaft and toward said predetermined quiescent position into closing engagement with said second switch.
